UNITED STATES PATENT OFFICE

JOHN KIRBY, JR., OF DAYTON, OHIO, ASSIGNOR TO THE DAYTON MANUFACTURING COMPANY, OF DAYTON, OHIO.

DESIGN FOR AN ELECTRIC-LAMP FIXTURE.

45,465.

Specification for Design.

Patented Mar. 24, 1914.

Application filed January 23, 1914. Serial No. 813,997. Term of patent 7 years.

To all whom it may concern:

Be it known that I, JOHN KIRBY, Jr., a citizen of the United States, residing at Dayton, county of Montgomery, and State of Ohio, have invented a new, original, and ornamental Design for Electric-Lamp Fixtures, of which the following is a specification.

The design is illustrated in the accompanying drawing, to which reference is made, and in which the design is shown in full perspective.

The general contour of the fixture is clearly illustrated in the drawing. It comprises a central supporting hanger adapted to be secured to a ceiling, a plurality of arms radiating from the supporting

hanger, outwardly and downwardly, to an annulus.

The fixture is designed to carry a translucent dome above the annulus and a translucent bowl therebelow, but as these features do not constitute part of my design for a lamp fixture they are represented in dotted lines, merely to illustrate their relation thereto.

I claim:

The ornamental design for a pendent lamp fixture, as shown and described.

JOHN KIRBY, Jr.

Witnesses:

H. D. HENDRICK,
P. LEIDENGER.
